ATTORNEY

UNITED STATES PATENT OFFICE

HOWARD E. MAYNARD, OF DETROIT, MICHIGAN, ASSIGNOR TO CHRYSLER CORPORATION, OF DETROIT, MICHIGAN, A CORPORATION OF DELAWARE

WRENCH

Application filed February 23, 1929. Serial No. 342,072.

This invention is illustrated as embodied in a wrench used for the removal of a hub cap from an automobile wheel hub.

The present trend in the design of automobile hub caps is to provide a large circular face on the front of the hub cap which makes the multi-sided neck or nut portion inaccessible with the usual wrench adapted to fit over the end of the hub cap.

10 End wrenches may be used to engage the nut, but such are objectionable in that they slip around the nut portion due to the fact that they only engage approximately one half of the nut. If these wrenches are slightly 15 sprung they no longer fit the nut portion.

It is an important object of this invention to provide a pivoted engaging face on a wrench which may be opened to fit over the nut portion and then closed to engage faces 20 on the nut portion at points less than 180° apart or engage more than two of the nut faces.

Another object of the invention is to provide the pivoted engaging face of the wrench 25 and the wrench handle so that as the handle is moved in one direction the engaging surfaces of the wrench are brought together more tightly, engaging the nut portion.

Another object of the invention is to pivot 30 the jaws of a wrench which may be opened to fit over the multi-sided portion of the cap and adapted to be closed to engage faces of the multi-sided portion less than 180° apart.

Another object of my invention is to provide 35 a simple two piece stamping formed from sheet metal that will be light, durable and compact in size and to form engaging flanges bent at right angles to the body portion of the stamping to increase the nut engaging area of the wrench.

The above and other objects of the invention will be more fully understood from the following description taken in connection with the accompanying drawings, in which:

45 Fig. 1 is a side elevation of a hub cap with my improved wrench applied thereto.

Fig. 2 is a plan view of the wrench showing the nut portion of the hub cap in section taken on line 2-2 of Fig. 1, viewed in the 50 direction indicated by the arrows.

Fig. 3 is a side elevation of the hub cap with a portion of the wrench in section taken on line 3-3 of Fig. 2, viewed in the direction indicated by the arrows.

Referring to the drawings, I have shown 55 an automobile wheel hub 10 and a hub cap 12. The cap 12 is composed of an internally threaded portion 14; a multi-sided neck portion 16, which will be hereinafter referred to as the nut portion, and a circular ornamental 60 face portion 18.

It will be apparent from the design of the hub cap 12 that an open ended wrench, either adjustable or fixed, is the only type of wrench 65 that could be used to remove the cap 12 from the hub 10. It has been found that the use of conventional open ended wrenches for thin soft metal hub caps is impractical.

I have designed a combination open end 70 and clamp wrench consisting of only two parts, a handle 20 and a U shaped head portion 22. A rivet 24 secures the two parts together and acts as a pivot about which either 75 may turn relative to the other. The part 22 has an ear 26 stamped in it, which is bent around upon itself and forms a bearing for the rivet 24. Both the handle 20 and the head portion 22 have projections 28, which are bent upward at right angles to the plane 80 of the pieces 20 and 22, and act as a means for increasing the area exposed to the face of the nut portion 16. It will be noted that the ear 85 26 has been turned over on the same side of the head as that from which the projections 28 extend.

In the operation of my improved wrench the parts are relatively pivoted about the rivet 24 far enough so that the U shaped member 22 may be slipped over the nut portion 16 of the hub cap much in the same manner as 90 an open ended wrench. The handle 20 is then pivoted back about the rivet 24 in a direction for applying or removing the cap until the projection 28 comes in contact with the nut 16, clamping the same between the engaging faces of the handle and the U shaped end piece. Further movement of the handle will 95 turn the hub cap. The cap is clamped so tightly between the engaging faces 28 of the handle 20 and the end piece 22 that there is 100

no tendency for the wrench to slip around the nut.

Although I have described but one form of my invention, it is to be understood that I do not intend to be limited to the structural details of my device except by the terms of the appended claims.

What I claim is:

1. In a device of the class described, a U shaped stamping; nut engaging shoulders upturned about the inner periphery of said U shaped stamping for engagement with a plurality of faces on a nut; an ear turned back upon itself at one end of said U shaped stamping and on the same side as the aforesaid shoulders; a pin passing through the ear and stamping, and a handle pivoted on said pin and adapted to engage another face of a nut in said wrench.
2. In a device of the class described, comprising a U shaped head portion adapted to engage a nut on three sides thereof; upturned flanges about the inner periphery of said head to increase the nut engaging surface thereof; an ear turned back upon itself at one end of the head portion and on the same side as the upturned flanges; a pin passing through said ear and head; a handle pivoted on said pin and adapted to engage a fourth side of a nut in said U shaped head portion.

HOWARD E. MAYNARD.
